UNITED STATES PATENT OFFICE.

LÉON VANDAM, OF UCCLE, BELGIUM.

DISINFECTION APPARATUS.

SPECIFICATION forming part of Letters Patent No. 746,413, dated December 8, 1903.

Application filed June 13, 1903. Serial No. 161,381. (No model.)

To all whom it may concern:

Be it known that I, LÉON VANDAM, engineer, a subject of the King of Belgium, residing at 44 Avenue du Longchamps, Uccle, Belgium, have invented a new and useful Disinfecting Apparatus; and I do hereby declare the following to be a full, clear, and exact description of the same.

This invention has for its object to provide an improved disinfecting apparatus for use in connection with beer-barrels, wine-casks, and the like in breweries, wine-producing installations, fermenting-rooms, and similar places, whereby the complete destruction of bacteria can be effected.

The leading advantage of the apparatus is that it permits of the disinfecting liquid to be mixed with an appropriate volume of dry steam for the production of a gaseous disinfectant.

The apparatus suitable for this purpose is shown in the annexed drawing by way of example only.

The reference-letter A denotes the admission-pipe, fitted with a stop-valve for the ingress of dry steam.

B is the mixing-pipe (in continuation of pipe A) for mixing the steam with the disinfecting liquid, which is delivered through the pipe C, fitted with a funnel-shaped mouth at its outer end.

D is a receiver or vessel containing the disinfecting liquid and having a draw-off cock R situated over the mouth of the pipe C for the delivery of the disinfecting medium,

which after being mixed with the dry steam passes in gaseous form through the egress-pipe E for its delivery into the room or space to be disinfected.

The operation is as follows: The disinfectant—say formaldehyde, formol, sulfuric acid, chlorin, or the like—is drawn off from the vessel D through the cock R and runs through the mouth of the pipe C toward the mixing-pipe B, where it meets the dry steam from the pipe A and becomes gasified. The mixture of dry steam and disinfectant is forced by the steam-pressure into the room or space requiring to be disinfected.

What I claim is—

In a disinfecting apparatus a vertical pipe leading to the part to be disinfected and having an enlarged portion, a steam-injector pipe having a nozzle located in said enlarged part, a branch pipe communicating with said enlarged part above the end of steam-nozzle, said branch pipe having an upturned end provided with a funnel, a reservoir for disinfecting fluid located over said funnel, and a delivery-nozzle provided with a regulating-cock for controlling the flow of the fluid into said funnel, substantially as described.

In testimony whereof I have signed this specification in the presence of two subscribing witnesses.

LÉON VANDAM.
